UNITED STATES PATENT OFFICE.

AUGUST C. RADER, OF READING, MASSACHUSETTS.

WINDOW-CURTAIN FIXTURE.

Application filed April 13, 1920, Serial No. 373,487. Renewed April 11, 1922. Serial No. 551,470.

To all whom it may concern:

Be it known that I, AUGUST C. RADER, a citizen of the United States, residing at Reading, in the county of Middlesex and 5 State of Massachusetts, have invented a new and useful Window-Curtain Fixture, of which the following is a specification.

This invention relates to window curtain fixtures especially designed for use in connection with the curtains of street cars and the like. In fixtures of this character it is the practice to have members projecting beyond the sides of the curtain for engaging the window casing so as to hold the curtain 15 at any position to which it might be moved.

One of the objects of the present invention is to simplify and otherwise improve upon the construction of the fixture used for this purpose, reducing the number of parts 20 to the minimum and providing a structure which is compact, durable and efficient and the parts of which can be assembled readily in the process of manufacture.

With the foregoing and other objects in view, which will appear as the description proceeds, the invention resides in the combination and arrangement of parts and in the details of construction hereinafter described and claimed, it being understood, 30 that, within the scope of what is claimed, changes in the precise embodiment of the invention shown can be made without departing from the spirit of the invention.

In the accompanying drawings the preferred form of the invention has been shown.

In said drawings—

Figure 1 is a view partly in elevation and partly in section of a portion of a window curtain having the present improvements 40 combined therewith.

Figure 2 is an enlarged section through one of the fixtures, the finger engaging portion being removed.

Figure 3 is an end elevation of the fixture. 45 Figure 4 is a section on line 4—4, Figure 2.

Figure 5 is a perspective view of the tubular shank of the fixture.

Referring to the figures by characters 50 of reference A designates a window shade having the usual tubular housing B in the free transverse edge thereof, this housing containing the fixtures employed for holding the shade at desired positions and which 55 fixture constitutes the present invention.

Each of the fixtures in the present instance

includes a tubular body member 1 exteriorly screw-threaded at 2 so as to engage interior threads within one end portion of the housing B. This body portion has a 60 tubular shank 3 extending from one end thereof, said shank being rectangular in cross section and being provided with a cylindrical opening 4 extending therethrough. Grooves 5 are formed in opposed 65 faces of the shank directly opposite each other. A lock nut 6 engages the exterior threads of the body 1 and is adapted to bind against the end of the housing B, thus to hold the body 1 against movement after it 70 has been properly adjusted in the housing.

The angular shank 3 projects through an angular opening 7 formed in the intermediate portion of an elongated yoke 8 and mounted in the end portions of this yoke 75 are bearings 9 on each of which is supported a roller 10 provided with parallel annular grooves 11.

Slidably mounted within the body 1 and also within the housing B is a rod 12 which 80 projects outwardly through the opening 4 and has its outer end secured within a friction block 13 provided with parallel bores 14 extending thereinto from end to end. Spring wires 15 are fitted loosely within 85 the grooves 5 and are bent upon themselves so as to fit snugly within the grooves 11 and the two rollers 10, the free ends of these wires projecting into the ends of the bores 14 as shown particularly in Figure 2. Thus 90 it will be seen that the spring wires 15 hold the body 1 and the yoke assembled and normally in a predetermined relation and at the same time maintain the friction block 13 in a predetermined position relative to the end 95 of the angular shank 3. A finger piece 16 of the usual or any preferred type is extended from that end of the rod 12 remote from the block 13 and by pressing thereagainst the rod 12 can be shifted longitudinally so as to move the block 13 toward the shank 3 and at the same time place the end portions of the wires 15 under increased tension. When the block is thus shifted the

curtain A can be moved readily from place 100 to place and when the finger piece is released the block 13 will be shifted outwardly by the ends of the spring wires 15 until it frictionally engages the window frame. The yoke 8 and the parts carried thereby can 105 now be shifted bodily inwardly relative to the body 1 and the rod 12 in which event

those portions of the wires engaging the grooves 5 will flex as will also the end portions of the wires engaging the block 13. By thus mounting the structure so that both 5 the yoke and the block are capable of movement relative to the body although the parts are held by the same spring, the structure is rendered very efficient in operation because of the ease with which it will follow 10 any irregular contours. This construction is also advantageous because of the few parts employed, the simplicity of construction, and the readiness with which the parts can be assembled.

15 What is claimed is:

1. A curtain fixture including a tubular housing having an angular end portion, an actuating rod slidably mounted within and projecting through the housing, a yoke 20 slidably mounted on said angular portion of the housing, a friction block mounted on one end of the rod, rollers journaled in the yoke, and a spring straddling the rollers and engaging the housing and block to yieldingly 25 hold both the rollers and the blocks against movement relative to the housing.
2. A curtain fixture including a yoke, spaced rollers carried thereby, a tubular body projecting into the yoke and slidably 30 engaged thereby, an actuating rod movably mounted in the body, a friction block secured thereto and supported between the rollers, and a spring straddling the rollers and engaging the block and body to hold the 35 same yieldingly in a predetermined relation.
3. A curtain fixture including a tubular body, a yoke slidably mounted thereon, an actuating rod extending through the body, a friction block secured to the rod, rollers

carried by the yoke and at opposite sides of 40 the block, and a spring straddling the rollers and engaging the body and block to hold them normally in a predetermined relation, said block being movable relative to those portions of the spring engaging the same. 45

4. The combination with a body having a groove therein, a yoke loosely mounted on the body, and means carried by the yoke for engaging a window frame, a friction block, an actuating rod connected to the friction 50 block and movable relative to the body, of a spring extending loosely within the groove in the body and movably engaging the block to hold the rod, block and body normally in a predetermined relation. 55

5. The combination with a body having a grooved end portion, the grooves being disposed in opposite portions of the body, of a yoke loosely mounted on the body and held against rotation relative thereto, 60 grooved rollers carried by the end portions of the yoke, a friction block, an operating rod movable relative to the body and engaging the block, said block and body projecting between the rollers, and springs 65 loosely mounted in the grooves in the body and straddling the rollers, said springs being seated in the grooves in the rollers and having their terminals projecting into and slidably engaging opposite ends respectively 70 of the friction block.

In testimony that I claim the foregoing as my own, I have hereto affixed my signature in the presence of two witnesses.

AUGUST C. RADER.
